UNITED STATES PATENT OFFICE.

EDWIN WALDRON, OF COBLESKILL, NEW YORK.

CAR-COUPING.

SPECIFICATION forming part of Letters Patent No. 391,098, dated October 16, 1883.

Application filed February 7, 1888. Serial No. 263,275. (No model.)

To all whom it may concern:

Be it known that I, EDWIN WALDRON, of Cobleskill, in the county of Schoharie and State of New York, have invented new and 5 useful Improvements in Car-Couplers, of which the following is a specification.

My invention relates to improvements in mechanism for coupling together a series of railway-cars to form trains; and the object of 10 my invention is to provide a simple and reliable coupler by which the operation of coupling cars can be effected automatically. This object I attain by the mechanism illustrated in the accompanying drawings, which are herein 15 referred to and form part of this specification, and in which—

Figure 1 is a longitudinal section of the draw-heads of a pair of my couplers connected together, with the draw-bars and coupling eyes 20 shown in elevation. Fig. 2 is a plan view of a pair of my couplers connected together. Fig. 3 is an enlarged longitudinal section of one of my couplers, with the draw-bar and coupling-eye shown in side elevation; and Fig. 4 is a 25 transverse section of the bumper of the draw-head at the line X X on Fig. 3.

As represented in the drawings, A designates the draw-head of my coupler, which is made in a box-like form and is provided with 30 a bumper, 1, at its outer end and a centrally-perforated end piece, 2, at its inner end. Said bumper has a vertical slot, 3, formed for its own coupling-eye, and a transverse enlargement, 4, of said slot for the reception of the 35 coupling-eye of another coupler. In the bottom plate of said draw-head there is a slotted opening, 5, for a purpose hereinafter explained.

B is a draw-bar formed of two like side bars, 6, which are preferably connected together by 40 a cross-piece, 7, to operate as a single piece. The inner end of said draw-bar is connected to a draw-bolt, C, which projects rearwardly through the perforation of the end piece, 2, and is then surrounded by a spring, 8, that is arranged to operate in the usual manner of 45 coupler-springs. The draw-bar B is pivoted by a pin, 9, to the draw-bolt C, so as to vibrate in a vertical plane when occasion requires it.

D is the coupling-eye, provided with an arm, 10, by which said eye is connected by means 50 of a pivot-pin, 11, to the outer end of the draw-

bar B. The inner end of the arm of the coupling-eye has an inclined face, 12, against which, when said coupling-eye is in an erect position and the draw-bar in a horizontal position, as 55 indicated by dotted lines in Fig. 3, the coupling-eye of another coupler with which a connection is to be made will strike and thereby raise the outer end of the draw-bar B, to permit the coupling-eye of the second coupler to 60 pass under and form a connection therewith. The inner end of the coupling-eye D is also formed into a hook, 13, which enters the opening of the coupling-eye of a connecting coupler, as indicated by dotted lines in Fig. 65 1, to effect the locking together of two conjoining couplers. Preferably the coupling-eye D is held in its erect position by means of a latch-bar, 14, having both a swinging and a sliding movement, and for that purpose said 70 latch-bar is pivoted to a cam-shaft, 15, provided with a cam, 16, which is arranged in an arched top opening formed in the pivoted end of said latch-bar in such manner that when said cam is turned in one direction said latch-bar will 75 be moved forward to engage under a retainer, 17, and when the cam is turned in the opposite direction said latch-bar will be retracted from said retainer and left free to be swung over into the position indicated by dotted lines 80 in Fig. 4. When the coupling-eye D is raised into its erect position, its arm 10 will pass into the slot 3 of the draw-head A of the coupler to which it belongs.

E is a toggle joint, which is inserted in the 85 slotted opening 5 of the draw-head and whose lower member is secured to a shaft, 18, that should extend to the side or both sides of a car and there be provided with a crank-handle, 19, by which said shaft may be rocked 90 when occasion requires. The upper member of said toggle-joint is provided with a slotted opening, 20, through which a cross-pin, 21, secured in the draw-bar B, passes. The joint-pin 22 of said toggle-joint is arranged out of a direct line with the centers of the shaft 18 and cross-pin 21, so that a shouldered rule-joint will be formed between the two members of 95 said toggle joint, and thereby all liability of said toggle-joint being flexed by any jarring 100 or jolting of the cars will be avoided.

The coupling-eye D is maintained in posi-

tion when extended in line with the draw-bar B, as shown in the right-hand coupler of the pair shown in Fig. 1, by its hook 13, which engages under the cross-piece 7 for that purpose.

5 The operation of my coupler is as follows: The couplers being separated from each other, with the coupling-eye of one in an erect position, the draw-bar B being in a horizontal position, as indicated by the dotted lines in Fig. 10 3, and the coupling-eye of the coupler to which the connection is to be made being extended, as shown in the right-hand coupler of the pair shown in Fig. 1, the extended coupling-eye of the coupler last referred to is brought forcibly 15 into contact with the inclined face 12 of the erect coupling-eye, and thereby the outer end of the draw-bar to which the last-named coupling-eye is attached will be raised to permit the incoming coupling-eye to pass under the lower 20 end of the erect coupling-eye, and as soon as the last-named movement is accomplished the outer end of said draw-bar will drop to carry the hook 13 of its attached coupling-eye into the opening of the coupling-eye which has just 25 entered, as last described, and the connection of the two couplers is in this manner completed. To disconnect a pair of my couplers, the shaft 18 of the coupler whose coupling-eye D is standing in an erect position is turned to 30 bring its attached toggle-joint E into a straight line, as shown by the full lines of Fig. 3. Thereby the outer end of the draw-bar will be raised to release the hook 13 from the coupling-eye of the other coupler and leave the 35 pair of couplers free to be separated from each other.

I claim as my invention—

1. In a car-coupler, the combination of a

draw-head having a vertically-slotted opening in its outer end, a draw-bar pivoted at its inner end to a draw-bolt, so as to swing in a vertical plane within said draw-head, and a coupling-eye provided at its inner end with an inclined face and a hooked projection, said coupling-eye being pivoted to the outer end of the 45 draw-bar, so as to swing in a vertical plane into and out of the vertically-slotted opening of said draw-head, as and for the purpose herein specified.

2. In a car-coupler, the combination of a 50 coupling-eye pivoted to the outer end of a draw-bar, so as to swing in a vertical plane, a draw-head having a vertically-slotted opening for the reception of said coupling-eye when the latter is raised to an erect position, and a 55 locking device fixed to the outer end of said draw-head, whereby said coupling-eye can be secured in its erect position, as and for the purpose herein specified.

3. In a car-coupler, the combination of a 60 draw-head having in its outer end a vertically-slotted opening which extends into the upper side of its bumper, a draw-bar pivoted at its inner end to a draw-bolt, so as to swing in a vertical plane, a coupling-eye pivoted to the 65 outer end of said draw-bar to swing into said vertically-slotted opening of the draw-head, and a toggle-joint connected to the swinging end of said draw-bar for the purpose of lifting and securing the latter in its raised position, all being constructed and arranged to operate substantially as herein specified.

EDWIN WALDRON.
